DISPLAY

William M. Gardner and Mary C. Gardner, Pittsburgh, Pa., assignors to Gardner Displays Company, a corporation of Pennsylvania

Application March 17, 1941, Serial No. 383,710

8 Claims. (Cl. 46—119)

This invention relates to improvements in displays adapted for advertisement, amusement and other purposes.

One of the objects of our invention is to provide a display which is animated and is simple in construction and operation.

Another object of the invention is to provide a device which can be animated or operated by an increase or decrease of the air pressure inside the device.

A further object is the production of a display which may be readily moved into and out of view by a change in pressure of the air inside the device.

Still another object of the invention is an inflatable figure which can be animated without the aid of mechanical devices inside the figure itself. Complicated and life-like movements can be imparted to a display by relatively simple apparatus.

Other objects and advantages of the invention will be apparent during the course of the following description.

In the accompanying drawings we have shown for purposes of illustration only certain exemplary embodiments of our invention.

Figure 1 is a view partly in elevation and partly in vertical section of a display simulating part of a human body.

Figure 2 is a view of a detail of a portion of a body.

Figure 3 is an enlarged fragmentary view of a detail of the operating mechanism.

Figure 4 is a view in elevation of a display simulating an animal, portions of the base being cut away.

Figure 5 is a perspective view of a display device simulating a refrigerator, with a portion of the inflated wall of the device broken away to reveal a detail of structure.

Figure 6 is a view partly in elevation and partly in vertical section of the structure shown in Figure 5, a part thereof being in collapsed condition.

Figure 7 is a view partly in side elevation and partly in vertical section of another display device, and

Figure 8 is a view in elevation of the front of the device shown in Figure 7.

In Figure 1 of the drawings, there is shown a display device which simulates the upper portion of a human body. The body consists of a hollow trunk portion 10, two hollow arms 11, each terminating in a hand 12, and a hollow head 13 joined to the trunk by the hollow neck por-

tion 14. The arms and head are in communication with the hollow space inside the trunk. The body is preferably made from a flexible airtight or substantially air-tight fabric or material. We prefer to use a fabric which is relatively non-extensible although various parts of the figure, such as parts of the head, may be made from an extensible air-tight material, e. g., rubber. To obtain desirable effects, certain portions of the figure may be made from material which has a flexing quality differing from that possessed by the material from which other portions of the body is made. For example, each of the elbow portions 15 of the arms 11 may be made from material which is more flexible or less flexible than the material from which the remainder of the arm is formed. The shoulder portion 16 and the neck 14 may likewise be made of fabric having flexing qualities differing from those possessed by the other material. So also the head 13 could be made flexible or inflexible and the features made of materials more flexible or less flexible than the material of which the rest of the head is made. By a judicious selection and arrangement of materials it is possible to make a figure to which attractive and eye arresting movements can be imparted by controlling and changing the pressure of the air inside the figure.

The base of the figure is secured in air-tight engagement to the top 17 of a stand or base 18. A low pressure blower 19 is disposed inside the stand and from the blower an air pipe 20 extends into the hollow trunk 10 and terminates just above the top 17. Leading from the inside of the figure to the stand 18 is a fairly large circular opening 21 in which is seated a valve 22 that is hingedly connected at 23 to the top 17, so as to open upwardly into the interior of the figure. The valve is operated by a lever 24 which is urged so as to close the valve by the spring 25 and is moved in the opposite direction to open the valve by the rotatable cam 26. The cam 26 has lobes of varying height, spaced unequally apart. This gives what appears to be unpredictable and irregular movements to the figure. The valve is made fairly large so that a relatively small movement thereof will permit a fairly large amount of air to rapidly escape and appreciably affect the pressure inside the figure and consequently the movement of the parts. The cam 26 is designed so that the valve 22 is closed until the figure is inflated and thereafter the valve is opened and closed at predetermined or intermittent intervals as desired. This per-

mits the pressure to be relieved and re-established and the change in air pressure causes movement of the various parts of the figure. After a desired interval of time the valve may be opened widely enough to cause the pressure to drop to atmospheric or nearly atmospheric and the figure thus deflates and collapses. An enlarged view of cam 26 is shown in Figure 3.

The blower 19 and the cam 26 are both driven by a motor 27 through pulley and belt connections 29 and 28, respectively. In order to ensure that the trunk 10 will not, when collapsed, foul the valve 22, or the discharge end of pipe 20, a screen 30 is provided to overlie the valve and the end of the pipe and to project upwardly inside the trunk 10.

When there is no air under pressure being supplied, the figure will be in a deflated or collapsed condition and will lie closely adjacent the top 17 of the stand, where it can be readily hidden from view by an appropriate screen 31 (shown in dotted lines). Soon after the blower 19 is put in operation the figure will be inflated and as the valve 22 is opened and closed the various parts of the figure will be caused to move due to the relief and re-establishment of the air pressure.

Erratic movements can be imparted, say to an arm, by the provision of a shifting weight, the movement of which will change the center of gravity of the arm. In Figure 2, we show an arm in which a metal ball 32 is placed. The arm 11a is shaped so that when in the elevated position the elbow 15a is below the shoulder and the hand. A perforate flexible screen 33 adjacent the elbow extends across the hollow space in the arm. As the pressure is relieved the hand 12a will drop to a level below the elbow portion and the weight will shift toward the hand and hasten the dropping of the arm.

In Figure 4 there is shown a display simulating an elephant. The elephant has a hollow body 34, hollow legs 35, a hollow tail 36, a hollow head 37, hollow ears 38 and a hollow trunk 39. The display is covered with a flexible substantially air-tight material, having portions of differing degrees of flexibility, e. g., portions of the legs, tail, trunk, ears, neck, etc. A blower 40 under the stand 41 supplies air to the body through a front leg. A valve 42, operated by a cam 43, is located in one of the other legs and controls the discharge of air from the figure. The cam 43 and the blower 40 are both driven by a motor 44. The cam 43 is so designed that the valve 42 is closed until the figure is inflated and after the figure is inflated the valve is opened and closed at desired intervals, regular or irregular for a predetermined length of time. The valve is then widely opened and the figure collapses and drops behind the screen 45. The cam 43 can be similar to cam 26 shown in Figure 3. The change in air pressure causes various parts of the animal's body to move.

In Figures 5 and 6, there is shown a screen or shroud 46 which surrounds, when inflated, the sides of an article 47, here a modern refrigerator. When collapsed, the screen drops into a space 48 around the bottom of the article displayed. The shroud 46 has hollow sides 49 and 50 of flexible air-tight fabric spaced apart to form a hollow air space 51. The front and sides of the shroud are decorated to represent the front and sides of an old fashioned refrigerator. At intervals hoops 52 are secured to the fabric walls 53

to prevent bulging of the walls when the shroud is inflated.

The bottom of the shroud terminates in an enlarged portion or manifold 53 having walls of material less flexible than the material of which the walls of the shroud are made, or the material may be substantially rigid. A blower 54 forces air under pressure into the manifold 53 and thence into the hollow space between the walls. A relief or exhaust valve 55 similar to that already described (22) is also provided in the manifold walls. This valve is opened and closed by a cam 56, which at stated intervals opens and closes the valve. When the blower is in operation and the valve closed, the walls of the shroud 46 will be inflated and will rise and surround the refrigerator 47 and give the appearance of an old fashioned refrigerator on display. When the valve 55 is opened the air pressure will be decreased or relieved and the side walls 49 and 50 will drop down into the space 48 and the modern refrigerator 47 will be revealed. In Figure 6 the walls of the shroud are shown collapsed, in which condition the walls are hidden.

In Figures 7 and 8 there is shown a display which consists of an article to be shown such as a modern refrigerator 57, the face 58 of which is on view behind, for example, a show window 59. A hollow screen 60 is arranged between the window and the face of the article 57. The screen is made from flexible air-tight material having a space between the layers. The bottom of the screen connects with a manifold 61 into which air is blown at low pressure by means of a blower 62. A valve 63, similar to the release valve 22—already described, is arranged in the manifold. The valve is opened by means of a cam 64 similar to cam 56 already described. Cross rods 65 extend horizontally across the screen inside the front wall and are secured thereto. The ends of the rods 65 are hooked to the guide rods 66 which extend from brackets 67 to a position below the top of the stand 68. This arrangement prevents undesirable billowing of the four walls of the screen and positively guides the screen. In many instances it will be unnecessary to provide guide means and anti-billowing devices. Similar rods 69 may be arranged to prevent billowing of the rear walls if desired. To aid in collapsing the screen, biasing means, such as a metal bar 70, can be attached to the screen.

The face of the screen 60 is prepared to resemble, when extended, the face of an old fashioned article of the kind displayed, e. g., an old fashioned refrigerator. The screen is raised to extended position by air from the blower 62, when the valve 63 is closed. When the valve 63 is kept opened by the action of the cam 64 the screen 60 will collapse into the space 70 between the stand 68 and the face of the refrigerator support 71. The modern refrigerator is then revealed. The screen 60 will also collapse if the blower is stopped. Means for periodically stopping and starting the motor which drives the blower are well known and form no part of this invention.

A valve 78 controls the passage of air to the duct 76 and branch 77. A valve 79 controls the passage of air through the duct 73 and branch 75. The valves are connected by an operating linkage to the hinged lever 80. By appropriate movement of lever 80, either manually or automatically, the valves 78 and 79 may be set to

cause the blower to inflate or deflate the device connected to the manifold 61a.

We have found that a suitable pressure is from about two pounds per square inch to about five pounds per square inch, but pressures smaller or greater may be employed. The pressure chosen will depend on the degree of flexibility of the material used and the size of the article to be inflated. In general the larger the article the higher the pressure, but it should be borne in mind that it is desirable from the standpoint of economy to utilize as low a pressure as possible.

While we have shown certain exemplary embodiments of our invention it will be apparent that the invention may be embodied in many other types of apparatus and that changes in the shape, size and arrangement of the apparatus may be made without departing from the scope of the claims.

We claim as our invention:

1. A device of the class described comprising a hollow inflatable unicellular body formed from substantially air-tight flexible material, portions of said material being substantially inextensible and other portions being extensible, means for continuously supplying air to the interior of the body and automatic means separate from said air supplying means for relieving and re-establishing the pressure at intermittent intervals.

2. A device of the class described comprising a collapsible inflatable body, means whereby a substantial volume of air is continuously introduced into the body and tending to inflate the body, automatic means separate from said first mentioned means for intermittently varying the extent of inflation, and separate means secured to the body for controlling the shape of the inflated body.

3. A device of the class described comprising a collapsible inflatable body, means for continuously supplying a constant volume of low pressure air to the interior of the body, automatic means separate from said first mentioned means for intermittently varying the extent of inflation, and means for varying the center of gravity of a portion of the body.

4. A device of the class described comprising a collapsible inflatable body, means whereby a

substantial volume of air is continuously introduced into the body and tending to inflate the body, automatic means for intermittently varying the extent of inflation, and means secured to the body for urging a part of the body downwardly.

5. A device of the class described, including a hollow base, a collapsible inflatable body secured to the base, a blower in said base, a discharge pipe leading from the blower into the body and in constant communication with the body, said base having an opening of relatively large size between the base and the body a valve in said opening and means for opening and closing the valve at predetermined intervals.

6. A device of the class described, including a hollow base, a collapsible inflatable body secured to the base, a blower in said base, a discharge pipe leading from the blower into the body and in constant communication with the body, a valve interposed between the base and the body means for opening and closing the valve at predetermined intervals and means in said body overlying the valve for preventing the material of the body from fouling the valve.

7. A device of the class described, including a hollow base, a collapsible unicellular inflatable body secured to the base, a blower in said base, a discharge pipe leading from the blower into the body and in constant communication with the body, said base having an opening between the base and the body and means for opening and closing the opening at predetermined irregular intervals.

8. A device of the class described, including a hollow base, a collapsible inflatable body secured to the base, a blower in said base, a discharge pipe leading from the blower into the body and in constant communication with the body, a valve interposed between the base and the body means including a cam rotatably driven for opening and closing the valve at predetermined intervals and means in said body overlying the valve for preventing the material of the body from fouling the valve.
